UNITED STATES PATENT OFFICE.

RICHARD L. BARRETT, OF CHICAGO, ILLINOIS.

CARBURETER.

1,113,533.

Specification of Letters Patent.

Patented Oct. 13, 1914.

Application filed July 19, 1911. Serial No. 639,339.

To all whom it may concern:

Be it known that I, RICHARD L. BARRETT, a citizen of the United States, residing at Chicago, in the county of Cook and State of Illinois, have invented certain new and useful Improvements in Carbureters, of which the following is a specification.

My invention relates to carbureters and refers particularly, although not exclusively, to carbureters such as are used on automobiles, motor-boats, and the like.

It is one of the objects of my invention to so construct the nozzle and parts associated therewith that a very perfect atomizing of the hydro-carbon fuel is effected and this finely divided fuel is perfectly mixed with the air introduced into the carbureter. In this way, it is possible to operate the engine at a low speed and, on account of the perfect mixture which is obtained even with a slight vacuum in the engine, the latter may be very easily started and excessive cranking, which is often necessary when carbureters of the types at present in use are employed, may be avoided.

A further object of my invention is to provide means by which the amount of liquid fuel admitted to the mixing chamber is automatically increased as the throttle is opened.

A further object of my invention is to entirely separate the admission of auxiliary air from that of the primary air which passes through the nozzle.

These and other advantages of my invention will be more apparent by reference to the accompanying drawings which represent a preferred embodiment of my improvements, and in which—

Figure 1 is a side elevation of the carbureter and a float chamber associated therewith; Fig. 2 is a vertical longitudinal section through the carbureter and float chamber shown in Fig. 1; Fig. 3 is a plan of the carbureter, the float chamber being omitted for the sake of simplicity; Fig. 4 is a horizontal section taken on the line 4—4 of Fig. 2, a portion of the float chamber being omitted; Fig. 5 is an enlarged vertical section through the nozzle; Fig. 6 is a section on the line 6—6 of Fig. 5, and Fig. 7 is a fragmentary sectional view on the line 7—7 of Fig. 3, the adjusting screws being shown in elevation.

The carbureter of my invention comprises two main castings, made of brass or other

similar metal, namely, the lower casting 10 and the upper casting 11. As shown in Figs. 1 and 2, the lower casting 10 is provided with the flange 12 which receives the tube 13 within which is thus formed the float chamber 14. To the upper end of the tube 13 is fastened the top 15 by means of the screws 16. The casting 10 is tapped in line with the central axis of the float chamber 14 and a hollow plug 17 is screwed into the aperture thus formed. This plug has a central chamber 18 and a passage 19 connected therewith which communicates directly with the inside of the float chamber 14. On its exterior the plug has the projecting collar 20. On the lower end of the plug 17 is screwed the cap nut 21 which engages the flanged sleeve 22, suitable packing 23 being inserted between the cap nut 21 and the sleeve 22 and also between the latter and the annular projection 24 of the casting 10. The sleeve 22 has the lug 25 to which is fastened the gasoline pipe 26 by means of the nut 27. Between the inner surface of the sleeve 22 and the outer surface of the plug 17, is formed the annular space 28 in which is placed the circular strainer screen 29, the lower edge of this screen engaging the upper edge of the cap nut 21 and the upper edge of the screen engaging the annular projection 20 of the plug 17. Between the annular space 28 and the chamber 18 within the plug 17 are the apertures 30 which allow passage of gasoline flowing into the annular space 28 from the pipe 26 to the chamber 18.

Passing through the lug 31 of the top 15 and also through the passage 19 of the plug 17 is the valve stem 32 which has the enlarged beveled end 33. As clearly shown in Fig. 2, the passage 19 is somewhat larger in diameter than the valve stem 32 in order to allow the passage of gasoline from the chamber 18 to the float chamber 15 when the valve stem is depressed so that the beveled end 33 is removed from its seat at the lower end of the passage 19. Freely movable on the valve stem 32 is the float 34 which in its lowermost position is supported on the upper end of the plug 17. The valve stem 32 is provided with a series of apertures 35 by means of which the collar 36 may be placed in a desired position. It will be evident that as gasoline enters the float chamber 14, the float 34 will be moved upwardly on the valve stem 32 until it comes

- in contact with the collar 36. The valve stem itself will then be carried upwardly until the end 33 of the valve stem 32 is seated on the lower end of the passage 19 whereby the further admission of gasoline is prevented. The collar 36 is adjusted on the stem 32 so that the desired level of gasoline may be obtained in the float chamber before the admission of further gasoline is cut off.
- 10 Communicating with the bottom of the float chamber 14 is the passage 37 through the casting 10, this passage turning in an upward direction and passing through the nozzle receiving member 38 which is preferably integral with the casting 10. Into the upper end of the member 38 is screwed the nozzle 39. The construction of this nozzle is most clearly shown in Figs. 5 and 6. The passage 37 continues upwardly through the 20 central part of the nozzle which consists of an upper portion 40 and a lower portion 41. The lower portion 41 has the threaded lug 42 which is screwed into the end of the member 38, as just explained, and also has 25 the flanged portion 43 at the outer edge of which is the angular groove 44. The upper surface of the lower portion 41 is provided with the annular rib 45 in which are the grooves or ports 46. Passing vertically 30 through the flanged portion 43 is a plurality of air passages 47, these air passages preferably being of the same number as the ports 46 in the rib 45 and located on radii of the nozzle which pass intermediate between the 35 grooves 46. The object of this construction will be explained hereafter.
- The upper portion 40 of the nozzle 39 has a substantially vertical periphery 48 with the downward extending flange 49 which fits 40 into the groove 44 of the lower portion 41 of the nozzle. The lower surface 50 of the upper portion 40 engages the rib 45 and a thin slit 51 is thereby formed between the upper portion 40 and the lower portion 41 45 of the nozzle 39. Air passages 51 are provided through the upper portion 40, these preferably tapering outwardly in an upward direction and registering with the passages 47 of the lower portion 41.
- 50 Integral with the lower casting 10 is the flange 52 which receives the casing 53 of the mixing chamber 54, this casing being cylindrical and preferably of glass in order that the operation of the carburetor may be 55 clearly seen.
- Inside of the flange 52 is the annular upward extension 55 in which is a plurality of apertures 56. Also integral with the casting 10 is the U-shaped downward extension 57 60 comprising the outer wall 58 and the inner wall 59 thereby forming the annular chamber 60. The outer wall 58 is provided with a plurality of apertures 61 which thus afford communication between the chamber 60 and 65 the outer atmosphere. To the lower edge

of the downward extension 57 is attached the sleeve 62 by means of the screws 63. This sleeve 62 is provided with the inwardly extending bearing collar 64, the object of which will be explained hereafter. The lower edge of the sleeve 62 is threaded for the reception of the adjusting cap 65. This cap has a knurled edge 66 by means of which the cap may be readily rotated. This cap is held in its adjusted position by means of the spring actuated locking pins 67 which engage suitable vertical corrugations in the sleeve 62. The lower surface of the cap 65 is provided with the openings 68 through which air may readily pass. Attached to the cap 65 is the rod 69 having on its upper end the plate or pin 70 which is engaged by the upper end of the conical coiled spring 71, the lower edge of which engages the horizontal portion of the angular flange 72 attached to the lower end of the valve sleeve 73. As clearly shown in Fig. 2, the valve sleeve 73 engages the collar 64 of the sleeve 62 and the upper edge of the inner wall 59 of the U-shaped downward extension 57 and on its inner surface engages the outer surface 48 of the upper portion 40 of the nozzle 39 and is thus guided in its vertical movement which will presently be explained.

Suitably attached to the valve sleeve 73 is the valve member 74 which operates on the inner surface of the upward extension 55, the lower edge of the valve member being adapted to become seated in the angular groove 75. By this construction, it will be apparent that the valve member 74 must be lifted slightly before air can pass from the annular space 60 through the apertures 56 into the mixing chamber 54.

The upper casting 11 is provided with a flange 76 to receive the upper edge of the casing 53 of the mixing chamber and is attached to the lower casting 10 by means of the rods 77 which pass from the lugs 78 to the lugs 79, these rods being secured in position by means of the nuts 80 and 81. Rigidly attached to the inside of the casting 11 is the throttle sleeve 82 having therein the apertures 83. Between this sleeve and the outside of the casting 11 is formed the annular chamber 84. Rotatable within the throttle sleeve 82 is the throttle 85 having apertures 86 which are adapted to be brought into register with the apertures 83 of the throttle sleeve 82. This throttle is also provided with a top 87 having an upwardly extending lug 88. Passing downwardly through a suitable aperture in the lug 88 and fitting loosely therein is the needle valve stem 89 which passes into the aperture 90 of the upper portion 40 of the nozzle 39, this aperture 90 being of slightly larger diameter than the passage 37 through the lower portion 39 of the nozzle.

When the valve stem 89 is in its lowermost position its beveled end 91 is adapted to seat on the upper end of passage 37 in the lower portion 41 of the nozzle 39.

5 Rigidly clamped to the lug 88 of the throttle 85 is the throttle lever 92, the inner end of this lever being split and clamped to the lug 88 by means of the screw 93. Also fastened to the lug 88 by means of the 10 screw 94 is the semi-circular compensator platform 95 having on its outer edge the flange 96. This compensator platform is provided with the lugs 97 and 98 through which pass the abutment screws 99 and 100. 15 Pivotaly attached to the lug 97 by means of the pin 101 is the cam 102, the opposite end of which is carried by the lower end of the adjusting screw 103, which is best shown in Fig. 7. This screw 103 has threaded engagement with the bracket 104 mounted on the compensator platform 95. This adjusting screw 103 is provided on its shank with the longitudinal grooves 105 engaged by the spring controlled locking pin 106 which 20 serves to hold the adjusting screw in any position in which it may be placed.

Clamped to the upper end of the valve stem 89 is the compensator member 107 provided with the slot 108 (shown in Fig. 3), 30 and secured in position by means of the screw 109. This compensator member has the flanged end 110 under which the compensator platform is rotated by means of the lever 92. The opposite end of the compensator member 107 is provided with the 35 recess 111 containing the spring 112 which incloses the screw 113, the upper end of this spring engaging the head of the screw 113 and the lower end engaging the bottom 40 of the recess 111. The screw 113 has threaded engagement with a suitable aperture 114 in the upper casting 11 while the compensator member 107 is vertically movable with respect to the said screw. In this way the 45 compensator member 107 and the valve stem 89 attached thereto may be moved upwardly against the tension of spring 112 but are prevented from rotation.

The adjusting screw 115 held in adjusted 50 position by the spring controlled locking pin 116 passes through the compensator member 107 and is adapted to engage, on its lower end, the cam 102.

Connected with the annular space 84 out- 55 side of the throttle sleeve 82 is the passage 117 which is adapted to connect with a suitable passage leading to the engine in the well known manner.

Having thus described the construction 60 of the various parts which constitute the embodiment of my invention herein set forth, the operation of the same may now be readily understood: Gasolene flows through the inlet pipe 26 into the annular chamber 28 and thence through the strainer

screen 29, through the aperture 30 into the chamber 18. From this chamber gasolene flows through the passage 19 into the float chamber 14 until the float 34 has been raised a sufficient distance so that the beveled end 70 33 of the valve stem 32 is seated against the lower edge of the passage 19. Meanwhile, the gasolene which has entered the float chamber 14 passes into the passage 37 of the casting 10 and the member 38 until the 75 heights of gasolene in this passage and in the float chamber are the same. The height should be maintained preferably slightly below the slit 51 which separates the upper portion 40 from the lower portion 41 of the 80 nozzle 39. If it is desired to prime the carbureter before starting the engine, this may readily be accomplished by manually depressing the valve stem 32 thereby causing the gasolene to rise in the float chamber 14 85 and the passage 37 so that the same will flow downwardly over the member 38 and the spring 71. I find, however, that in practice my carbureter works so efficiently that it is generally unnecessary to perform any 90 priming.

When the carbureter is used for the first time and it is desired to adjust the compensator mechanism, the lever 92 is moved to the right, according to the showing of Fig. 25 3, until the abutment screw 99 comes in contact with the end 110 of the compensator member 107. The abutment screw 99 is then adjusted so that the minimum desired opening of the throttle 85 is obtained. The 10 adjusting screw 115 is now turned in order to obtain the desired adjustment of the needle valve 89 with respect to the nozzle 39. This adjustment being secured, screw 103 is next adjusted so that the desired 10 sloping position of the cam 102 is obtained. The correct adjustment may readily be effected by moving the lever 92 to the left until the abutment screw 100 engages the end 110 of the compensator member 107, 11 whereby the valve stem 89 is lifted and the screw 103 is then adjusted to move cam 102 to give the desired position of valve stem 89 for the maximum opening of the throttle 85. The degree to which this throttle may 11 be opened may, of course, be regulated by a suitable adjustment of the abutment screw 100.

In order to readily mount the carbureter in any style of motor car, the lever 92 may 12 be attached to the lug 88 in any desired position as, for example, that indicated by dotted lines in Fig. 3 in which case the lever would be moved to the right in order to open the throttle instead of to the left as 12 would be the case if the lever occupies the position shown in full lines.

Having attained the desired adjustment of the compensator and throttle, the latter is 13 opened to the desired extent and the engine

is cranked. The suction thereby resulting in the engine causes the air to pass through the opening 68 of the cap 65 through the space contained within the valve sleeve 73. This air then continues upwardly passing through the comparatively small openings 47 of the lower portion 41 of the nozzle 39 and its velocity is thereby greatly increased. In passing through openings 47 and the registering openings 51^a of the upper portion 40, the suction thereby created causes the gasoline to be drawn from the passage 37 into the slit 51 and thence through the small ports 46 of the annular rib 45. The gasoline is thereby finely atomized and follows the course indicated by arrows in Fig. 6, a large portion of the gasoline being thrown outwardly against the flange 49 and a portion passing directly to the lower ends of the openings 51^a, this effect being produced by the location of the ports 46 between the apertures 47. In this way a thorough mixture of the finely divided gasoline and air takes place.

25 In Fig. 2 the lever 92 is shown in an intermediate position, but for the sake of clearness the openings 86 and 83 are shown as exactly registering with each other.

When the throttle is opened beyond a certain extent, the air passing through apertures 47 and 51^a is not sufficient to give the desired mixture, the compensator having raised the valve stem 89 to an extent corresponding to that to which the throttle has been opened. The increased suction which is caused by thus opening the throttle causes the pressure of the atmosphere within the annular chamber 60 to raise the valve member 74 and the valve sleeve 73 against the tension of the spring 71, in this way allowing air to flow through the openings 56 into the lower part of the mixing chamber 54. It will be apparent that on account of the mechanical construction of the spring 71 the tension on said spring increases only slightly as the same is compressed, thereby readily allowing the valve member 74 to be lifted to the desired extent and causing a ready and free admission of air. I prefer to use the substantially round apertures 56 for the admission of auxiliary air in order that the air may flow through a comparatively wide space, thus avoiding the noise which results when air flows through a narrow slit. The auxiliary air which is thus admitted by the opening of the valve member 74 effectually prevents the condensation of gasoline in the lower part of the mixing chamber, and as this air passes upwardly it is gradually drawn toward the central axis of the mixing chamber and mixes with the mixture of primary air and gasoline, which has been introduced through the apertures 51^a.

65 The regulation of the admission of auxil-

iary air may readily be effected by a proper adjustment of the cap 65, thus regulating the tension of the spring 71.

It will be clear to those skilled in the art that many changes could be made in the detailed construction of the various parts which I have described without departing from the spirit or scope of my invention.

What I claim is:

1. In a carbureter, the combination of a casing having a mixing chamber therein, and a nozzle communicating with said chamber, said nozzle having a liquid fuel inlet passage and an outlet slit extending radially therefrom and a plurality of air passages intersecting said slit, whereby the fuel and the air will be intimately mixed, substantially as described.

2. In a carbureter, the combination of a casing having a mixing chamber therein, a nozzle communicating with said chamber, said nozzle having a liquid fuel inlet passage and an outlet slit extending radially therefrom, a plurality of air passages intersecting said slit, and means between said fuel inlet passage and said air passages for finely dividing said fuel, whereby when the latter comes in contact with the air an intimate mixture will be obtained, substantially as described.

3. In a carbureter, the combination of a casing having a mixing chamber therein, a nozzle communicating with said chamber, said nozzle having a liquid fuel inlet passage and an outlet slit extending radially therefrom, a plurality of air passages intersecting said slit, and an apertured rib in said slit between said fuel inlet passage and said air passages, whereby the fuel will be finely divided and an intimate mixture will be obtained between the fuel and the air flowing through said air passages, substantially as described.

4. In a carbureter, the combination of a casing having a mixing chamber therein, a nozzle communicating with said chamber, said nozzle having a liquid fuel inlet passage and an outlet slit extending radially therefrom toward but not reaching the periphery of said nozzle, and a plurality of air passages extending through said nozzle and intersecting said slit, substantially as described.

5. In a carbureter, the combination of a casing having a mixing chamber therein, a nozzle communicating with said chamber, said nozzle having a liquid fuel inlet passage and an outlet slit extending from said inlet toward but not reaching the periphery of said nozzle, a plurality of air passages through said nozzle and intersecting said slit, and an apertured rib in said slit between said air passages and said inlet passage, the apertures of said rib being radially located between said air passages, whereby a por-

tion of the fuel flowing through the apertures of said rib will be deflected to the outer edge of said slit before mixing with the air flowing through said passages, substantially 5 as described.

6. In a carbureter, the combination of a casing having a mixing chamber therein, said chamber having a plurality of inlet apertures in its lower portion, a nozzle communicating with said mixing chamber, means for supply liquid fuel to said nozzle, a needle valve for regulating the admission of fuel to said nozzle, a throttle in said mixing chamber, means for actuating said throttle, means for moving said needle valve synchronously with said throttle, a valve normally closing the inlet apertures to said mixing chamber, a valve sleeve attached to said valve and engaging 10 said nozzle, the interior of said sleeve communicating with the atmosphere and supplying air to said nozzle and spring means coöoperating with said sleeve and controlling said valve and adapted to allow the actuation 15 of said valve on the opening of said throttle beyond a predetermined amount.
7. In a carbureter, the combination of a casing having a mixing chamber therein, a nozzle having an enlarged end portion, said 20 nozzle provided with a vertically disposed fuel passage therethrough, a relatively thin slit extending radially from said passage, and a plurality of air passages intersecting said slit, substantially as described.
8. In a carbureter, the combination of a casing having a mixing chamber therein, a nozzle having an enlarged end portion and fuel and air passages therethrough, and a sleeve engaging the enlarged portion of said 25 nozzle, the interior of said sleeve being in communication with the air passages through said nozzle, substantially as described.

9. In a carbureter, the combination of a casing having a mixing chamber therein, a 45 nozzle having an enlarged end portion, said nozzle provided with a vertically disposed fuel passage therethrough, a relatively thin slit extending radially from said passage, and a plurality of air passages intersecting 50 said slit, a sleeve inclosing said nozzle and engaging its enlarged portion, the interior of said sleeve being in communication with said air passages and the atmosphere, and an auxiliary air inlet to said mixing chamber 55 exterior to said sleeve, substantially as described.

10. In a carbureter, the combination of a casing having a mixing chamber therein, a nozzle having an enlarged end portion, said 60 nozzle provided with a vertically disposed fuel passage therethrough, a relatively thin slit extending radially from said passage, and a plurality of air passages intersecting 65 said slit, a sleeve inclosing said nozzle and engaging its enlarged portion, the interior of said sleeve being in communication with said air passages and the atmosphere, an auxiliary air inlet to said mixing chamber exterior to said sleeve, and a valve for said 70 auxiliary air inlet integral with said sleeve, substantially as described.

11. In a carbureter, a nozzle comprising a pair of members connected with each other, a fuel passage extending through said 75 nozzle, the space between said members constituting a radial slit in communication with said fuel passage, and a plurality of air passages extending through said nozzle and intersecting said slit, substantially as de- 80 scribed.

RICHARD L. BARRETT.
